WATER PITCHER

Robert J. Franklin, New York, N.Y., assignor to
Schenley Industries, Inc., New York, N.Y.

Filed July 27, 1971, Ser. No. 166,652

Term of patent 14 years

Int. Cl. D7—01

U.S. Cl. D7—60

FIG. 4

FIG. 5

FIG. 1 is a side elevational view of a water pitcher, embodying my new design;

FIG. 2 is a right hand end view thereof;

FIG. 3 is a top plan view thereof;

FIG. 4 is a left hand end view thereof; and

FIG. 5 is a longitudinal sectional view thereof.

I claim:

The ornamental design for a water pitcher, as shown.
